(57) **CLAIM**

The ornamental design for pair of chain pulls, as shown and
described.

DESCRIPTION

The present invention relates generally to chain pull designs for attachment to the end of chains for controlling ceiling fan operations, and more specifically, to chain pull designs having a shape indicative of a fan and a light bulb for controlling those fan operations.

FIG. 1 is a perspective view of a fan-shaped chain pull design and a light bulb-shaped chain pull design attached to the ends of chains for controlling ceiling fan operations showing my new design;

FIG. 2 is a front elevational view of the fan-shaped chain pull design of FIG. 1;

FIG. 3 is a rear elevational view of the fan-shaped chain pull design of FIG. 1;

FIG. 4 is a top plan view of the fan-shaped chain pull design of FIG. 1;

FIG. 5 is a bottom plan view of the fan-shaped chain pull design of FIG. 1;

FIG. 6 is a left side elevational view of the fan-shaped chain pull design of FIG. 1;

FIG. 7 is a right side elevational view of the fan-shaped chain pull design of FIG. 1;

FIG. 8 is a front elevational view of the light bulb-shaped chain pull design of FIG. 1;

FIG. 9 is a rear elevational view of the light bulb-shaped chain pull design of FIG. 1;

FIG. 10 is a top plan view of the light bulb-shaped chain pull design of FIG. 1;

FIG. 11 is a bottom plan view of the light bulb-shaped chain pull design of FIG. 1;

FIG. 12 is a left side elevational view of the light bulb-shaped chain pull design of FIG. 1; and,

FIG. 13 is a right side elevational view of the light bulb-shaped chain pull design of FIG. 1.

The broken lines shown in FIG. 1 represent the portions of the
design which form no part of the claim.
